PATRICK J. McELROY, OF EAST CAMBRIDGE, MASSACHUSETTS.

Letters Patent No. 78,987, dated June 16, 1868.

IMPROVED NURSING-BOTTLE.

The Schedule referred to in these Letters Patent and making part of the same.

TO ALL WHOM IT MAY CONCERN:

Be it known that I, PATRICK J. McELROY, of East Cambridge, in the county of Middlesex, and State of Massachusetts, have invented an Improved Combined Breast-Pipe or Pump and Nursing-Bottle; and I do hereby declare that the following, taken in connection with the drawings which accompany and form part of this specification, is a description of my invention sufficient to enable those skilled in the art to practise it.

My invention relates to the construction of a breast-pump, with reference to adapting the same for use both as a breast-pump and as a nursing-bottle.

The invention consists, primarily, in making a nursing-bottle of a form to fit upon the breast, and with a nipple-tube fitting into the mouth thereof, (said nipple-tube being made removable,) and with a flexible tube leading from the outlet of the bottle, said tube being of length sufficient to reach from the breast to the mouth, and having a suitable glass or rigid mouth-tube, so made as to be adapted to the attachment of the rubber mouth-tube for use by the sucking babe.

Now, a breast-pipe has been made with a glass nipple-tube, and a flexible pipe, to lead from the milk-receiving bottle to the mouth, to draw the milk from the breast, but such nipple-tube is fixed to or forms part of the milk-receiving bottle, and is not adapted for use as a nursing-bottle, and the common nursing-bottle is simply a bottle with a cork, through which extends the rubber nipple-pipe, a glass tube leading to the bottom of the bottle to prevent inhalation of air from the bottle, but such a bottle is not adapted for use as a breast-pipe, and has never, to my knowledge, been so constructed that it could possibly be used for such purpose.

In my invention, by making the milk-receiving bottle in peculiar shape, and with provision for applying a removable breast-nipple tube, and with a flexible mouth-pipe, having provision for application both of the mouth of the mother and the mouth of the babe, I am enabled to make an instrument equally well adapted for use either as a breast-pipe or pump, or as a nursing-bottle.

The drawing represents a central section of an instrument embodying my invention.

a denotes the milk-receiving and supplying glass bottle, made oblong in shape, and so that it may rest horizontally upon a table, as seen in the drawing, it being large at one end, and with an inlet, *b*, at top, near said end, the glass being drawn down to a small outlet-tube or neck, *c*, at the opposite end, this outlet-end being elevated, so that when the bottle is laid down, the milk must flow back and away from this outlet, even if the bottle is otherwise full.

The bottle is made somewhat broad, and shallow in depth, so that it may be easily inserted within the dress and against the breast, and to the inlet *b* I apply a breast-nipple tube, *d*, having a flange, *e*, to fit around the nipple, and a tube to fit over the nipple, and lead the milk into the bottle, the outer surface of the tube being covered with rubber, *f*, to pack the nipple-tube, or make its connection with the bottle impervious. The outlet *c* is contracted near the end thereof, so as to form a bulbous neck, by which to attach and hold the end of a flexible pipe, *g*, and into the outer end of this pipe *g* a glass mouth-piece or tube, *h*, is crowded, the outer end of this tube being designed for application of the lips of the mother, or for application of the artificial nipple *i*.

The instrument is used as follows:

When the milk is to be drawn from the breast, the nipple-tube *d* is pressed tightly into the inlet *b*, and by means of this nipple the bottle is applied to the breast. The mouth-piece *h*, on the flexible pipe *g*, is then carried to the mouth, and by exhaustion of air from the bottle the milk is drawn from the breast. The bottle is then removed from the breast, and if the bottle is to be concealed within the dress, the nipple-tube *d* is removed, and replaced by a suitable stopper. The artificial nipple *i* is then applied to the tube *h*, when, by tipping the bottle so that the milk will be kept up to the small end of the bottle, the milk may be freely drawn from the bottle by the babe, the same as from an ordinary nursing-bottle.

I claim the milk-receiving and delivering bottle *a*, when combined with a breast-nipple tube, *d*, and having an outlet, *c*, flexible pipe *g*, mouth and nipple-attaching-tube *h*, and artificial nipple *i*, all arranged to operate substantially as described.

PATRICK J. McELROY.
